UNITED STATES PATENT OFFICE.

WALTER H. PUMPHREY, OF NEW YORK, N. Y.

DESIGN FOR A WEIGHING-MACHINE CASE.

SPECIFICATION forming part of Design No. 35,316, dated November 26, 1901.

Application filed October 17, 1901. Serial No. 79,048. Term of patent 14 years.

To all whom it may concern.

Be it known that I, WALTER H. PUMPHREY, a citizen of the United States of America, and a resident of the city of New York, county 5 of New York, State of New York, have invented and produced a new and original Design for a Weighing-Machine Case; and I declare the following to be a full, clear, and exact description of the same, reference being had to the accompanying drawings, forming part thereof, in which—

Figure 1 is a view in front elevation, illustrating a weighing-machine case embodying my design; and Fig. 2 is a side view thereof.

15 As shown in the drawings, the leading or material features of my design are as follows: The column A, rising from a suitable base, said column being of circular cross-section and uniform diameter throughout its length; 20 the enlarged rounded superstructure B, and

the section C, interposed between and connecting said column and superstructure, said section C, as viewed in Fig. 1, tapering downward from the rounded superstructure toward the column, its lower end, as viewed 25 in Fig. 2, being beveled and provided with an opening in the beveled portion through which the column passes.

Having described my invention, what I claim as new, and desire to secure by Letters 30 Patent, is—

The design for a weighing-machine case, as herein shown and described.

In testimony whereof I have signed my name to this specification in the presence of 35 two subscribing witnesses.

WALTER H. PUMPHREY.
